Plamme & Dorn

Attorney

UNITED STATES PATENT OFFICE.

JOSEPH M. PERRY, OF MAYFIELD, PENNSYLVANIA.

NUT LOCK.

Application filed April 23, 1925. Serial No. 25,364.

To all whom it may concern:

Be it known that I, JOSEPH M. PERRY, a citizen of the United States, residing at Mayfield, in the county of Lackawanna and State of Pennsylvania, have invented certain new and useful Improvements in a Nut Lock, of which the following is a specification.

This invention relates to an improved nut lock of the type wherein especially constructed auxiliary means is carried by the nut and the bolt is reconstructed to accommodate said means.

More particularly, I propose to provide the bolt with circumferentially spaced longitudinal key ways, and to provide the nut with a spring pressed key which is permanently carried thereby and which is receivable in any one of the key ways to prevent accidental rotation of the nut about the bolt or longitudinal slippage on the bolt.

The particular details employed for accomplishing this result will become apparent from the following description and drawing.

In the accompanying drawing forming a part of this application and in which like numerals are employed to designate like parts throughout the same:

Figure 1 is a top plan view of a nut and bolt constructed in accordance with my idea.

Figure 2 is an enlarged section and elevational view showing the structure more plainly and indicating the locking or retaining means in effective position.

Figure 3 is a horizontal section.

Figure 4 is a perspective view of the retaining key.

Figure 5 is a central vertical section through the nut showing one of the keyways in elevation.

Referring to the drawings in detail, the reference character 1 designates a bolt, which in order to adapt it to the present invention is provided with a plurality of circumferentially spaced keyways 2 extending through the free end as shown.

The chief feature of the present invention is the nut 3. This is the usual hexagonal, square, or other form of nut, and in the present instance it is provided in one side with a vertical groove 4 opening through the screw threads as shown in Figure 5. This groove is enlarged at a point between its ends as indicated at 5 to provide a seat

of the shape shown in the figure last named. The groove 4 is adapted for reception of a slidable key 6. This key is simply in the form of a strip of metal of polygonal cross section fitted in the groove and adapted to be projected from the same into one of the aforesaid keyways 2 in the bolt. In Figure 4 it will be noted that the key is provided on opposite sides with segmental projections 7 adapted to fit in the half-portions of the aforesaid circular seat 5. Also, at a point between these projections it is provided with a screw threaded hole 8. In this connection it will be observed that the stem of a screw or the like 9 extends through one side of the nut and into and through the seat 5 and is threaded into the hole 8. Furthermore, a coiled spring 10 surrounds this bolt, and bears at one end against the key, thus resisting the inward movement of the latter into the groove 4.

From the foregoing description it will be seen that normally, the small bolt 9 is turned in the manner to feed the key 6 into the groove 4 against the tension of the spring 10, the bolt then serving to hold the key in this position. The key is now in such a position as not to interfere with the placement of the nut 3 upon the bolt 1. Therefore, the nut is tightened in the usual way as if no auxiliary locking means were present. After the nut has been tightened to the desired degree it is given an additional turn, more or less, to position the key 6 opposite one of the adjacent keyways 2. The bolt 9 may now be turned to feed the key into the keyway as indicated in Figure 2. Obviously, when the key is thus forced into the keyway, it absolutely prevents accidental rotation, and possible subsequent loss of the nut 3. If desired, the bolt 9 may now be removed, for the key will be held firmly in place by the coiled spring 10.

It is thought that by considering the description in connection with the drawing, persons familiar with inventions of this class will be able to obtain a clear understanding of the same. For this reason a more lengthy description is thought unnecessary.

While the preferred embodiment of the invention has been shown and described, it is to be understood that minor changes coming within the field of invention claimed may be resorted to if desired.

Having thus described the invention, what I claim as new and desire to secure by Letters Patent is:—

In a structure of the class described, a nut provided with a vertical groove opening through the top and bottom and into the usual central screw threaded bore, there being a pocket formed at the center of the groove, a retaining key fitted into said groove, and having its ends flush with the top and bottom of the nut, said key being provided with a pair of projections slidably

disposed in said pockets and permitting transverse movement but preventing longitudinal movement of the key in said groove,¹⁵ a coil spring having one end disposed in said pocket and its other end bearing against said key, said key being formed with a screw threaded hole, and a retracting bolt carried by said nut and having its threaded shank extending into said screw threaded hole.²⁰

In testimony whereof I affix my signature.
JOSEPH M. PERRY.
